Patented Dec. 30, 1913.

UNITED STATES PATENT OFFICE.

EDWARD GIBBONS, OF FALL RIVER, MASSACHUSETTS

WINDOW-SHADE BRACKET.

1,083,082.

Specification of Letters Patent.

Patented Dec. 30, 1913.

Application filed April 22, 1913. Serial No. 762,840.

To all whom it may concern:

Be it known that I, EDWARD GIBBONS, a citizen of the United States, residing at Fall River, in the county of Bristol and State of Massachusetts, have invented new and useful Improvements in Window-Shade Brackets, of which the following is a specification.

The present invention relates to improvements in window fixtures for supporting shade rollers and curtain poles, the object of the invention being to provide a device of this character which may be easily and quickly positioned upon the frame of any ordinary window and sustained thereon by elements directly connected with the fixture, the said elements being so arranged as to obviate nailing the fixture as well as permitting the easy removal of the fixture.

With the above recited objects in view, and others which will appear as the nature of the invention is more fully understood, the improvement resides in the construction, combination and arrangement of parts set forth in the following specification and falling within the scope of the appended claims.

In the drawings: Figure 1 is a perspective view illustrating the fixture in applied position upon a window casing and supporting a shade roller and a curtain pole, Fig. 2 is a top plan view of the same, the dotted lines illustrating the various positions or angles which the pole supporting bracket may assume, Fig. 3 is a vertical longitudinal sectional view on the line 3—3 of Fig. 2, Fig. 4 is a transverse sectional view on the line 4—4 of Fig. 3, and illustrating a removable attaching element which co-operates with the hinged latch for retaining the fixture upon the casing.

Referring now to the drawing in detail, the numeral 1 designates an ordinary window casing and 2 my improved fixture or bracket which is adapted to be arranged upon the casing. The bracket comprises a flat body member 3 which is provided adjacent its lower portion with a pair of spaced openings 4 and 5 respectively, and at its top with inturned fingers 6 which have their extremities downturned and sharpened to provide knife points 7 which are adapted to enter the upper or horizontal member of the window casing. The body, diametrically opposite the opening 5, is formed with integral ears 8, the said body being constructed of resilient material, permitting the ears to exert a tension toward each other. The ears

are provided with openings for the reception of trunnions formed upon the arms 9 provided upon the upper bifurcated portion of a catch 10. This catch has its inner face provided with an inturned arcuate sharpened tooth 11, and the said tooth is adapted when the bracket is positioned upon the window casing to be forced by the catch 10 through the opening 4 and into engagement with the face of the casing, the peculiar shape of the teeth 11 causing the same to enter the casing at an angle to the said casing and also causing the entering point 7 of the finger 6 to be drawn tightly within the upper or longitudinal edge of said casing. The opening 5 is arranged directly between the arms 9 of the catch 10, so, if necessary, and as illustrated in Fig. 4 of the drawings, an additional securing element in the form of a tack 12 may be inserted into the said opening to within the casing, the head of the tack contacting with the arms 9 and effectively preventing the accidental outward swinging of the catch. From practice, however, it has been found that the employment of a tack is not essential, as the rounded formation of the tooth 11 prevents the direct outward movement of the catch, and furthermore, the ears 8 exerting a tension against the outer sides of the arms prevent the accidental swinging movement of the said arms in either direction.

Arranged upon what may be termed the inner edge of the bracket 2 is an integrally formed upwardly curved arm 13, the same being disposed at a right angle to the body, and the upper portion of the body is provided with a suitable opening 14 for the reception of the trunnion of said roller 15. The upper edge of the body is provided with an extension 16 and the end of this extension is curved upon itself to provide a socket 17 for the reception of one of the angular ends 18 of a guard pole supporting rod 19. The opposite angular end 20 of said rod is projected upwardly, or in an opposite direction to the angular end 18 of the said rod, and the end 20 is adapted to receive the sleeve 21 of a curved curtain pole support 22. By so constructing the rod 19 and providing the pole support with the sleeve 20 and the bracket 2 with the socket 17, it will be noted that the rod 19 may be swung to any desired angle with relation to the bracket, and also that the support 22 may be rotated to any desired angle with relation

2 to the rod 19, so it will be noted that the support may be adjusted toward or away from the casing 1, and also adjusted to receive curtain poles of varying lengths. It is to be understood that there is sufficient frictional engagement between the angular ends 18 and 20 of the rod 19 and the bores of the sleeve and socket to prevent the accidental swinging movement of the rod with relation to the bracket and to the curtain pole support, but if desired, and as illustrated by the dotted lines in Fig. 1 of the drawings, both the socket 17 and the sleeve 20 may be provided with threaded openings for the reception of threaded retaining elements in the nature of thumb screws. It will be noted that the end of the catch 10 is disposed a suitable distance below the bracket 2, when the said catch is swung to bring its tooth into engaging position, so that the extending portion of the catch may be easily grasped and the said bracket swung outwardly to bring its tooth out of engagement with the casing without the employment of a tool. It will be further noted that the tooth 11 is arranged centrally of, or directly between the fingers 6, so that the bracket is secured upon the casing at three distinct points, and whereby wobbling, longitudinal or lateral movement of the bracket, when secured upon the casing, is entirely overcome.

From the above description, taken in connection with the accompanying drawings, the simplicity of the device, as well as the advantages thereof will, it is thought, be perfectly apparent to those skilled in the art to which such inventions appertain without further detailed description.

Having thus described the invention, what I claim as new is:

1. A bracket for the purpose set forth comprising a body having its outer portion formed with offset fingers which terminate in angular sharpened points, a catch member hingedly connected with the body, said bracket member having a tooth which is arranged arcuately of the bracket and which is arranged central of the entering points of the fingers of the bracket.

2. A bracket support for window casings comprising a flat body having its upper por-

tion formed with right angular faces to have their extremities downturned and sharpened to provide entering points, a catch member hingedly connected with the bracket and having its end disposed below the end of the bracket, and the said catch having a centrally arranged inwardly curved sharpened tooth that is adapted to enter the face of the casing after the points of the fingers have been forced within the upper edge of the casing.

3. A removable bracket for window casings comprising a flat body having one of its ends provided with angular fingers which terminate in angular sharpened points, the said bracket adapted to have its body arranged against the casing and to have its points enter the upper edge of the casing, said bracket being provided upon its sides with out-turned fingers, a catch having trunnions received by the fingers, said fingers adapted to exert a tension upon the catch, the said catch having an entering tooth which is adapted to engage with the face of the casing, and the said catch when in catch engaging position projecting below the end of the bracket.

4. In a bracket of the class described for window casings, a flat body, said body having one of its ends provided with angularly arranged entering points which are adapted to be forced within the upper edge of the casing, the bracket having spaced openings, ears upon the bracket adapted to be arranged opposite the upper opening, a catch comprising a flat body having a bifurcated end to provide the same with arms, the said arms adapted to be pivotally connected with the ears, and the ears adapted to exert a tension against the arms, the said arms being disposed medially of the upper opening of the bracket, the catch having an arcuate tooth, and the said tooth adapted when the catch is swung against the bracket to pass through the second opening thereof and to enter the face of the casing.

In testimony whereof I affix my signature in presence of two witnesses.

EDWARD GIBBONS.
